ELECTRIC SWITCH

Vincent G. Apple, Dayton, Ohio, assignor to
 Bendix Brake Company, South Bend, Ind., a
 corporation of Illinois

Application January 13, 1936, Serial No. 420,375

8 Claims. (Cl. 201—51)

My invention relates to electric switches and has particular reference to an electric make and break unit wherein varying resistances are incorporated in the circuit during the movement of 5 the switch members per se.

As is quite generally known, a large and rapid change of current in any inductive or capacitive circuit produces a high internal voltage or potential, thereby straining the insulation and causing arcing or burning at slightly opened switch 10 points.

An object of my invention is to eliminate this destructive arcing where switches are used in circuits of this type by so inserting resistance 15 elements, as a portion of the switch itself, that the current strength or amperage is raised from a predetermined minimum to its full strength gradually but with sufficient swiftness to satisfy the requirements of the ordinary make and break 20 switch. To express the primary object of my invention somewhat differently, I have designed a switch which, when used in a circuit having an appreciable amount of inductance or capacity, causes a gradual change in opening or closing the 25 circuit thereby reducing the potential across the inductance or capacity.

Still another object of my invention has been to design a switch which, by utilizing resistance 30 elements of varying strength in conjunction therewith, may be utilized as a combination rheostat and circuit closing mechanism for many purposes. Among the varied applications which are obvious is its utilization with electric brakes for automotive vehicles.

Further objects and meritorious features of my 35 invention will become apparent from the following description taken in conjunction with the drawing wherein like numerals refer to like parts throughout and wherein:

Fig. 1 is a cross section through the axis of 40 my switch unit.

Fig. 2 is a cross section between the resistor 45 elements and through the central terminal.

Fig. 3 is a plan view of the resistor end, and

Fig. 4 is a circuit diagram of the electrical 45 connections for the switch as used in a circuit comprising a battery, an electric motor, and my switch.

In illustrating my invention I have disclosed 50 one preferred embodiment wherein the housing 10 is provided with two insulating tubes 12 in which are the resistance elements 14. These resistance elements I have indicated as carbon discs, although any other suitable resistance medium may be utilized. A metal plate member

16 connects the two resistance piles across their tops, while the plates 18 form a conductive bearing for the resistance elements 14. These plates 18 are insulated from the plate 20, which forms the bottom of my casing member, by means of 60 the washers 22. This bottom plate 20 is secured in place by means of screws 24. The bolts 26, which are held in place by the nuts 28 and insulated by the washers 30, provide an external connection to the plates 18. 65

Concaved plates 32 of spring metal material bear against the plate 16 and function as springs for the purpose of normally retaining the operative elements of my switch in the position shown in Fig. 1. These spring elements 32 likewise function to assist in graduating the pressure exerted on the carbon pile discs through the medium of the balls 34. 70

Discs 36 serve to insulate the plates 32 from the plates 38, upon which latter plates the balls 75 34 have a direct bearing.

The cam rod 39, which is free to slide axially in my casing member, as clearly illustrated in Figs. 1 and 2, is provided with peripheral grooves which are so located that when the said cam 80 rod is in its inoperative position (Fig. 1) movement in the direction of the arrow in Fig. 1 will first function to raise the ball 34 in the upper right hand corner of the quadrilateral formed by these four balls, then depress the lower left hand 85 ball, then the lower right hand ball, and finally force the upper left hand ball in an upward direction. It is likewise to be noted that the peripheral surface of this camming rod 39, at the end of each of the grooves, forms a concave portion 90 which serves to impart the pressure from the rods to the balls with gradually increasing force.

The upper balls 34 bear on the studs 40, the upper portion each of which is provided with a stem around which is placed a coil spring 42. 95 The contact bridge members 44 are seated at the base of the stem upon the stud 40, forming bearings for the coil springs 42, and in this way the said contact bridge members 44 are normally retained in their open position, bearing against the 100 balls 34.

The terminals 46 are threaded into the insulating cover 48 of my casing and secured in place by means of the nuts 50. A bracket member 52, secured to the casing by means of the screws 54, 105 serves as a support for the switch unit when it is desired to secure it to an automotive vehicle or the like.

Although the operation of my switch unit is obvious from the above description and the draw- 110

ing, a brief sketch of the various stages involved therein will be given.

When the cam rod 39 is pulled in the direction of the arrow (Fig. 1) the ball 34 in the upper right corner is forced upward thus closing the circuit through the terminals brought in contact with the corresponding switch blade 44. On further axial movement of the cam rod 39 the lower left hand ball 34 will bear down on the plate 38 and transmit the pressure through the plates 32, 36, and 16 to the left hand pile of carbon discs, thereby decreasing the resistance in this particular pile. Further movement of the cam rod causes pressure to be applied to the lower right hand ball 34, decreasing the resistance in the right hand pile of carbon discs in the same manner. At this particular point the current strength or amperage may be regarded as in its third stage and the resistance in the circuit at its minimum value. On still further movement of the cam rod 39 the upper left hand ball 34 is forced upward and the left hand contact blade bridges its terminals. This final movement cuts both of the carbon disc piles out of the circuit entirely and a free flowing current of maximum amperage results.

Reference to Fig. 4 of the drawing will suffice to clearly illustrate the manner in which my plurality of resistance elements are first incorporated in the circuit on initial movement of the cam rod and subsequently shunted out of circuit at the final stage of its movement.

Various modifications of my device will be apparent to those skilled in the art and for that reason I intend to limit myself only within the scope of the appended claims.

I claim:

1. An electric circuit control member comprising a housing, a pair of carbon disc piles adjacent one another within the housing, terminals connecting the base of each of said carbon piles with the exterior of the housing, a plurality of contact plates supported in the upper portion of the housing and provided on the exterior thereof with terminal facilities, camming means axially slideable through said housing, and means whereby axial movement of said camming means varies the resistance in said carbon piles successively.

2. An electric circuit control member comprising a housing, carbon disc piles located adjacent one another within said housing, terminal connections between each of said piles and the exterior of said housing, a plurality of contact plates located within said housing and provided with terminal facilities on the outside thereof, contact bridge members adapted to be actuated to bridge said contact plates and normally retained in open circuit position with respect thereto, and means operable to bridge two of said contacts and then for successively applying varying pressures upon each of said piles of carbon discs.

3. In combination with a plurality of carbon piles, a pair of normally open switch elements, and a single means associated with each for successively closing one switch, varying the resistance through the carbon piles successively, and closing the other switch.

4. An electric switch comprising a casing, a trio of contacts supported thereby, switch blades operable to bridge said contacts consecutively, a pair of carbon piles housed within said casing, and slideable camming means associated with said switch blades and carbon piles operable to first close one pair of contacts, then vary the pressure within each pair of carbon piles successively, and subsequently close the second pair of contacts.

5. In an electric circuit a switch including a plurality of contacts, a plurality of resistance elements the resistance of which varies under pressure, a control device, means responsive to the initial movement of said device to bridge two of said contacts and make the circuit through said plurality of resistance elements, means responsive to further continued movement of said device to successively compress said resistance elements reducing the resistance thereof successively, and means responsive to still further continued movement of said device to bridge two other contacts shunting the resistance elements out of the circuit.

6. In an electric circuit a switch comprising a plurality of contacts, a plurality of resistors the resistance of which varies under pressure, a manipulable control member, means responsive to the initial movement of said control member to make the circuit through said plurality of resistors without varying pressure thereon, means responsive to further continued movement of said control member to vary the pressure on said resistors first compressing one of them to a minimum resistance and while holding the same at said resistance compressing the other to a minimum resistance, and means responsive to further continued movement of said control member to short circuit said resistors.

7. In an electric circuit a switch comprising a plurality of contacts and a plurality of resistors, a movable control shaft, a ball associated with said movable control shaft for each resistor and each pair of contacts, separate means associated with each ball responsive to the movement thereof in response to the movement of the control shaft, said control shaft balls and separate means adapted under movement of the control shaft to first bridge two contacts closing the circuit through said resistors and then to successively reduce the resistance in said resistors to a minimum for the combined resistors and then to bridge two other contacts shunting said resistors out of the circuit.

8. In an electric circuit, a self-contained switch including a plurality of resistors, a control member, cooperating switch mechanism operable upon movement of said control member to make the circuit through said plurality of resistors, means responsive to continued movement of said control member to successively vary the resistance through each of said resistors successively reducing the resistance therein, and second cooperating switch mechanism operable upon further continued movement of said control member thereafter to shunt said resistors out of the circuit.

VINCENT G. APPLE.
